No. 740,055.

PATENTED SEPT. 29, 1903.

M. F. STADTMULLER.
WINDOW PUTTY PROTECTOR.
APPLICATION FILED JUNE 29, 1903.

NO MODEL.

UNITED STATES PATENT OFFICE.

MAX F. STADTMULLER, OF POMEROY, IOWA.

WINDOW PUTTY-PROTECTOR.

SPECIFICATION forming part of Letters Patent No. 740,055, dated September 29, 1903.

Application filed June 29, 1903. Serial No. 163,605. (No model.)

To all whom it may concern:

Be it known that I, MAX F. STADTMULLER, a citizen of the United States, residing at Pomeroy, in the county of Calhoun and State 5 of Iowa, have invented certain new and useful Improvements in Window Putty-Protectors, of which the following is a specification.

This invention is designed to provide means for protecting the putty used to secure window-panes in position in the sash to prevent the putty from breaking or crumbling away, due to the extreme length of time it has been in position, and generally to preserve the putty in as permanent a state as possible. 10 Specifically the means consists of a peculiar form of protector-strip which is secured over the line of putty along the edges of the window-pane, the said strip or strips being held in place by peculiarly-formed clips, which are 15 secured by suitable means to the window.

For a full description of the invention and the merits thereof and also to acquire a knowledge of the details of construction of the means for effecting the result reference is to 20 be had to the following description and drawings hereto attached.

While the essential and characteristic features of the invention are susceptible of modification, still the preferred embodiment of 25 the invention is illustrated in the accompanying drawings, in which—

Figure 1 is a perspective view of a window-sash showing the embodiment of the invention. Fig. 2 is a view, parts broken away, 30 showing the manner of disposal of the strips when two or more of these are disposed in alinement, illustrating the manner of use when the invention is applied to a large-sized window. Fig. 3 is a perspective view of one of 35 the protector-strips. Fig. 4 is a combined view showing modified forms of clips for securing the strips to the window. Fig. 5 is a sectional view through a window-sash having the invention applied thereto.

Corresponding and like parts are referred to in the following description and indicated in all the views of the drawings by the same 40 reference characters.

In carrying out the invention it is contemplated that the same may be applied to the 45 ordinary structure of window-sash, there be-

ing no substantial modification of such structure in order to adapt the invention thereto.

1 designates the outer bars of the sash-frame, and 2 the inner narrow bar. The 55 panes are disposed upon the sash in the usual manner and are held in place by the putty 3, over which the protector-strips 4 are placed. The strips 4 are preferably made from sheet metal, such as tin, zinc, or the like, as found 60 suitable. The end portion of the adjacent strips are mitered, as shown most clearly at 5, so as to come together in such a manner as to make a neat joint. The strips are provided at intervals thereon with depressions 6, which 65 depressions are made therein by suitable machines for this purpose. The depressions 6 receive the inclined end portions 7 of clips 8, which are secured to the outer faces of the sash-bars 1 and 2. The clips 8 consist of the 70 attaching portions 9 and the inclined end portions 7, before mentioned, and are secured to the frame of the sash by means of screw-fastenings 10, which pass through perforations 11 therein. The clips disposed upon 75 the outer sash-bars of the frame are substantially alike, consisting of the portions 7 and 9, before described. The inner bar, however, is provided with special clips of arched form, 80 these clips being modifications as to structure of the clips above set forth, being provided merely with an additional inclined end portion, which gives them the form aforesaid. The arched clips thus have the perforation about centrally therein, and the ends overlap 85 the putty 3, which is located upon the sides of the inner bar. In securing the strips 4 to sash of large or small size it will be obvious that the length of the sash will determine the 90 number of strips which must be used to extend the entire length of the said sash. For instance, for some sash it will be necessary to use two or more strips in their relative alinement, and in securing the strips in position the end portions thereof are provided 95 with the depressions 6, and a single clip 8 overlaps and holds such end portions together.

The depressions in the strips 4 are necessarily embedded in the body of the putty 3, 100 and thus the strip is to a certain extent held above the putty. The attaching portions 9

of the clips are located in countersunk portions 12 upon the sash-bars, and therefore do not protrude above the surface of the said bars. The strips and clips are not noticeable 5 after the sash have been painted, and for this reason they are essentially advantageous in that they do not in any way affect the general appearance of the window. The strips are virtually universal in their use, since they 10 may be readily applied to almost any character of sash, and not only protect the putty from the general wear thereupon, but they are proof against water or any other foreign element. The assemblance of parts is cov- 15 ered in this invention to present extreme simplicity in their general use, and consequently they may be readily applied and removed without much expense of time or labor.

20 Having thus described the invention, what is claimed as new is—

1. The combination in means for securing window-panes in sash of putty or the like disposed adjacent the edge portions of the panes, 25 longitudinal protector-strips located above the said putty and provided at intervals thereon with portions pressed out of the plane of the body of the strips, and clips provided with at-

taching portions whereby same are secured to the sash-bars and having inclined end portions overlapping the protector-strips to hold the same in position, said inclined end portions being received by the depressed portions of the protector-strips. 30

2. The combination in means for securing window-panes in sash of putty or the like disposed adjacent the edge portions of the pane, protector-strips located above the aforesaid putty and having their meeting end portions mitered, said protector-strips being provided 40 with depressed portions at intervals thereon, clips, each comprising an attaching portion provided with an opening to receive fastening means for securing same to the sash-bars, and an inclined end portion overlapping the 45 protector-strip and received by the depressed portion thereof, and depressions disposed upon the sash-bars to receive the attaching portions of the clips.

In testimony whereof I affix my signature 50 in presence of two witnesses.

MAX F. STADTMULLER. [L.S.]
